ABSTRACT: A plurality of fixtures for securely holding together wooden beams in the form of a sawhorse, the fitting including for each sawhorse a pair of main brackets one of which is secured pivotally beneath each opposite end of the sawhorse backbone beam, a cap bracket for fitting over the upper end of each of the four sawhorse legs, and a pair of expander brace units, one set of each being secured to each of the pair of sawhorse legs.

FOLDING SAWHORSE BRACKETS

This invention relates generally to sawhorses.

A principle object of the present invention is to provide a sawhorse having self-contained means so that it can be conveniently fitted into a minimum amount of space or which can be conveniently transported on a vehicle by taking up minimum space.

Another object of the present invention is to provide a sawhorse which incorporates folding brackets so to permit the sawhorse legs to be pivoted between an extended and a retracted position.

Still another object of the present invention is to provide a pair of folding sawhorse brackets which are readily attachable to any conventional sawhorse so to make it the more easy to quickly collapse or to set up the sawhorse.

Other objects of the present invention are to provide a pair of folding sawhorse brackets which is simple in design, inexpensive to manufacture, rugged in construction, easy to use and efficient in operation.

These and other objects will be readily evident upon a study of the following specification and the accompanying drawing wherein:

FIG. 1 is a flat pattern view showing components of the present invention.

FIG. 2 is a perspective view of the main bracket fully formed.

FIG. 3 is a perspective view of one of the leg cap brackets shown fully formed.

FIG. 4 is a perspective view of an expander brace member formed up.

FIG. 5 is a cross-sectional view taken on the line 5-5 of FIG. 3.

FIG. 6 is a perspective view showing one end of a sawhorse and which incorporates the present invention.

FIG. 7 is a fragmentary perspective view showing the sawhorse backbone beam inverted upside down and showing the main bracket attached thereto.

FIG. 8 is an enlarged perspective view of the expander brace unit.

Referring now to the drawings in detail, the reference numeral 10 represents a folding sawhorse bracket assembly according to the present invention wherein there is a conventional sawhorse 11 that is comprised of a horizontally extending backbone beam 12 which at its opposite ends is supported upon a pair of sidewardly, downwardly diverging legs 13.

In the present invention, the pair of legs 13 at each end of the sawhorse are pivotable between an erected and a collapsed position as indicated by the arrow 14 in FIG. 6. This is accomplished by means of the pair of legs 13 being supported from a singular main bracket 15.

The bracket 15 shown in FIG. 2 is formed from a flat sheet metal blank 16 shown in FIG. 1, the main bracket 15 including a generally U-shaped main body having a flat wall 17 which is located between parallel flat walls 18 and 19. The wall 19 has a slot 20 for the purpose of receiving a pivotable latch tongue 21 of a latch 22 pivotable about a screw 23 inserted through opening 24 of the latch.

The other wall 18 has secured to opposite end edges thereof a pair of diagonally extending tabs or lugs 25 each provided with an opening 26 so to receive a mounting screw 27 and about which the main bracket is pivotable so that the legs may swing between an extended and a collapsed position, as indicated by arrow 14. When the sawhorse is erected, the wall 17 is positioned adjacent the underside wall 28 of the sawhorse backbone beam 12, as shown in FIGS. 6 and 7.

In this position, the slot 20 is in alignment for receiving the latch tongue 21, as shown in FIG. 7.

The upper ends of the legs are each fitted with a cap bracket 29 shown in FIG. 3 and which is formed of a blank 30 shown in FIG. 1. The cap bracket after being fully formed, as shown in FIG. 3, is shown to have an opening 31 on each opposite side thereof so to receive a mounting screw 32 by which the cap bracket is secured over the end of the leg 13.

The same opposite side walls 32 having the opening 31 are additionally provided each with an opening 33, the opening 33 receiving a bolt or rivet 34 which is additionally passed through an opening 35 formed near opposite ends of the walls 19 of the main bracket 15, and about which the cap bracket is pivotable so that the legs 13 may be drawn toward each other as indicated by arrows 36 in FIG. 6.

The present sawhorse construction additionally includes an expander brace unit 37 formed between each pair of legs 13, as shown in FIG. 6.

Each expander brace unit 37 includes a flat link 38 and an expander brace link 39 shown in FIG. 4 and which is formed from a blank 40, as shown in FIG. 1.

20 The link 38 is provided with openings 41 in the opposite end thereof while the expander brace link 39 includes openings 42 in one end thereof, the openings 42 being in alignment with each other, the opposite end of the expander brace link being provided with a slot 43, the slot 43 including spaced-apart notches 44 and 45 so as to selectively position a pin 46 extending therethrough and through the opening 41 at one end of the link 38.

The pin 46 includes enlarged heads 47 on opposite ends thereof so to prevent the same from accidentally falling out. It

30 will be evident that when the opposite end of the expander brace unit 37 is attached to the two legs 13 by means of screws 48, the brace will normally maintain the legs spread apart when the expander brace unit is extended in a straight line, as shown in FIG. 6.

35 When the legs 13 are drawn together, as indicated by arrows 36, the expander brace unit will fold upwardly into an A-configuration. The two notches 44 and 45 permit the expander brace unit to be adjustable in length so as to accommodate for looseness from wear or seasoning of the wood, and which can be quickly and easily accomplished by simply shifting the pin from one notch to the other.

Thus there is provided a novel sawhorse incorporating folding sawhorse brackets and associated construction.

What I now claim is:

45 1. In a folding sawhorse, the combination of a conventional sawhorse frame, said sawhorse frame including a horizontally extending backbone beam, the opposite ends of said backbone beam being supported upon two pairs of legs, each of said pairs of legs including two legs extending downwardly in a sidewardly diverging direction, and bracket means for pivotal movement of said legs respective to said backbone beam so that said sawhorse frame can be conveniently stored in a collapsed position when not in use, said bracket means including a main bracket attached pivotally free near each opposite end of said backbone beam, and an end cap bracket fitted over the upper end of each of said legs, said cap brackets each being pivotal respective to said main bracket, each main bracket comprising a generally U-shaped member having a flat wall for positioning against the underside of said backbone beam, said wall of said main bracket being located between the pair of parallel spaced-apart sidewalls, one of said sidewalls having an angle extended tab at each end thereof with a pivot opening for attachment pivotally free to said backbone beam.

50 2. The combination as set forth in claim 1, wherein the other said sidewall of said main bracket includes a pair of spaced-apart openings to each of which one of said cap brackets is attached pivotally free by means of a bracket rivet.
